(57) **CLAIM**

The ornamental design for a sink, as shown and described.

DESCRIPTION

FIG. 1 is an upper front perspective of a sink embodying my design;

FIG. 2 is a lower rear perspective of the sink shown in FIG. 1;

FIG. 3 is a front elevation of the sink shown in FIGS. 1 and 2;

FIG. 4 is a right side elevation of the sink shown in FIGS. 1-3, with the opposite side elevation being a mirror image thereof;

FIG. 5 is a rear elevation of the sink shown in FIGS. 1-4;

FIG. 6 is a top view of the sink shown in FIGS. 1-5; and,

FIG. 7 is a bottom view of the sink shown in FIGS. 1-6. The broken lines showing drain openings, plumbing features, and sink surfaces are for environmental purposes only and form no part of the claimed design.
